UNITED STATES PATENT OFFICE.

HENRY E. PIGGOTT, OF ST. LOUIS, MISSOURI, ASSIGNOR, BY DIRECT AND MESNE ASSIGNMENTS, OF PART INTEREST TO EDWARD B. ROTH AND WILLIAM H. BARNETT, BOTH OF SAME PLACE.

SMOKE-PREVENTER FOR FURNACES.

SPECIFICATION forming part of Letters Patent No. 400,709, dated April 2, 1889.

Application filed January 21, 1889. Serial No. 296,980. (No model.)

To all whom it may concern:

Be it known that I, HENRY E. PIGGOTT, a citizen of the United States, residing at the city of St. Louis, State of Missouri, have invented a certain new and useful Improvement in Smoke-Preventers for Steam-Boiler and other Furnaces, of which the following is a full, clear, and exact description.

My invention relates to an improved device for preventing smoke in steam-boiler and other furnaces, and has for its object to effect a thorough combustion of the gases and carbonaceous matter arising from the burning fuel in the furnace, and thereby prevent the escape of smoke into the chimney.

My invention consists in the features of novelty hereinafter described and claimed.

On the accompanying drawings, Figure 1 represents a front elevation of a steam-boiler furnace with my invention applied thereto; Fig. 2, a longitudinal sectional elevation thereof on line 1 1 in Fig. 1, broken away, with the smoke-preventer device seen in side elevation; Fig. 3, a detached longitudinal section of the device to an enlarged scale; Fig. 4, a side view thereof as seen in Fig. 2, to an enlarged scale; and Figs. 5, 6, 7, and 8 transverse sections on lines 2 2, 3 3, 4 4, and 5 5, respectively, in Fig. 3, like letters of reference 30 denoting like parts in all the figures.

a represents a steam-boiler furnace having the grate *b*, and constructed in the ordinary manner.

Above the front bearer or dead-plate, *c*, of 35 the grate *b* is arranged horizontally, and preferably in line with the upper stratum of the burning fuel one or more of my improved smoke-preventers, each of which is composed of a central nozzle-pipe, *d*, having at its rear 40 end, adjacent to the front of the boiler *e*, a chamber, *f*, which receives steam from the boiler *e*, through pipes *g*, which are provided with regulating-valves and arranged as shown, or in any other convenient manner.

From the inner closed end of the chamber 45 *f* passages *h* extend longitudinally through the wall of the nozzle *d* to a space, *i*, surrounding the reduced cylindrical front end portion of the nozzle *d*, and communicating 50 therewith a narrow annular passage, *j*,

which opens through the front end of the nozzle *d* into the furnace *a*.

In the nozzle *d*, at a suitable distance in front of the chamber *f*, is formed concentric with the annular passage *j* a central longitudinal passage, *k*, which opens through the front end of the nozzle *d* into the furnace *a*, and has transverse passages *k'* opening into a hood or casing, *l*, which surrounds the nozzle *d* at a suitable distance therefrom, and is 55 formed with openings *m* for the admission of air to the device. The front open end of the casing *l* may be extended by a pipe, *l'*, which opens at its front end into the furnace *a* at the level above referred to.

In operation, steam being admitted through the pipes *g* to the chamber *f*, as indicated by full arrows in Fig. 3, of the nozzle *d*, passes through the passages *h* into the space *i* and annular passages *j* around the front end portion of the nozzle *d*, from which it issues in the form of a thin cylindrical film into the pipe *l'* and furnace *a*. At the same time, owing to the partial vacuum induced within the casing *l* by the steam-film, air is drawn either 70 from the outside of the boiler or from the ash-pit or other suitable points, through the openings *m* into the casing *l*, as indicated by the dotted arrows in Fig. 3, where, surrounding the nozzle *d* and entering the central passage, 75 *k*, it is combined with and is impelled forward by the steam into the furnace *a*, so that an intense heat is thereby generated within the latter and a perfect combustion of the gases effected.

I claim as my invention—

1. In a steam-boiler or other furnace, the combination of a nozzle, *d*, having inlet steam-chamber *f*, communicating by passages *h* with annular space *i*, and outlet annular passage *j*, 90 and having a central passage, *k*, receiving air through inlet-openings *k'*, with means for admitting steam to chamber *f*, substantially as shown, and for the purpose described.

2. In a steam-boiler or other furnace, the 95 combination of a nozzle, *d*, having inlet steam-chamber *f*, passages *h*, annular space *i*, outlet annular passage *j*, and central passage, *k*, having inlet-openings *k'*, hood or casing *l*, surrounding the nozzle *d*, and having openings *m* 100

for receiving air, with means for admitting steam to chamber *f*, substantially as shown, and for the purpose described.

3. In a steam-boiler or other furnace, the combination of a nozzle, *d*, having inlet steam-chamber *f*, passages *h*, annular space *i*, outlet annular passage *j*, and central passage, *k*, having inlet-passages *k'*, hood or casing *l*, surrounding the nozzle *d*, and having extension-pipe *e* and openings *m*, with means for ad-

mitting steam to chamber *f*, substantially as shown, and for the purpose described.

In testimony whereof I affix my signature, in presence of two witnesses, this 18th day of January, 1889.

HENRY E. PIGGOTT.

Witnesses:

S. L. SCHRADER,

PAUL BAKEWELL.
